UNITED STATES PATENT OFFICE.

WILLIAM L. CLAUSE, OF PITTSBURGH, PENNSYLVANIA, ASSIGNOR TO PITTSBURGH PLATE GLASS COMPANY, A CORPORATION OF PENNSYLVANIA.

GLASS-DRAWING APPARATUS.

1,123,684.

Specification of Letters Patent.

Patented Jan. 5, 1915.

Application filed January 12, 1911. Serial No. 602,216.

To all whom it may concern:

Be it known that I, WILLIAM L. CLAUSE, a citizen of the United States, residing at Pittsburgh, in the county of Allegheny and State of Pennsylvania, have invented certain new and useful Improvements in Glass-Drawing Apparatus, of which the following is a specification.

This invention has reference to apparatus for drawing glass cylinders, and particularly to the mechanism for supplying pressure to the bait. It has for its primary objects; the provision of improved glass drawing mechanism whereby the pressure supplied to the bait is regulated and made uniform to secure an even and uniform cylinder and thus better the quality of the drawn glass; and the provision of improved mechanism for throttling and regulating the pressure supplied to the bait in the drawing operation. These together with such other objects as may hereinafter appear, or are incidental to my invention, I attain by means of a construction illustrated in preferred form in the accompanying drawings, wherein:—

Figure 1 is a representation of a glass drawing mechanism embodying my invention, and Fig. 2 is a view of a modified form of my invention.

Referring to Fig. 1 of the drawings, I have diagrammatically indicated a glass furnace 7, from which is being drawn a cylinder 9 by means of the bait 8. The bait 8 is provided with the usual blow pipe 10 and is guided and supported on the frame. The bait is raised by a hoisting or drawing cable 11, which is wound on a drum by the motor 12 through gearing 13. The motor is controlled by a controller 14 having four speeds for the different steps in the drawing operation.

The mechanism for supplying the proper pressures to the bait and cylinder during the various stages of the drawing will now be described. The blow pipe telescopes into a supply pipe 15 which supply pipe divides into two branches 16 and 17, each of which is provided with a fan 18 for generating air-pressure. The branches 16 and 17 of the supply pipe are also provided with upwardly projecting stems or tubes 19 and 20, on which are mounted water seal airometers 21 and 22. The airometers comprise a lower member or tank 23 provided with a double

wall and with an upper inverted bucket or tank 24, as clearly shown in Fig. 1. Butterfly valves 25 and 26 are provided in the branches of the supply pipe between the airometers and the fans, and are operated by means of ropes 27 secured to the buckets 24 and running over pulleys 28. At the junction of the supply pipe 15 and branches 16 and 17 is a two way valve 29 which is adapted to open and close communication between the branches and their respective airometers 65 and the supply pipe.

The purpose of the airometers and butterfly valves is to secure a uniformity of continuous established or predetermined pressures, and their operation is as follows. The buckets 24 and 24' are of different weights, the former being heavier than the latter, so that a higher pressure will be required to lift the bucket 24 than the bucket 24'. The pressures flowing from the branches 16 and 17 into the supply pipe 15 will consequently be different. In the present showing the buckets are weighted so that the pressures will be one ounce and two ounces respectively, and the weighting can be readily changed to further vary the pressures to suit different conditions. The higher pressure is used to form the neck portion of the cylinder and the lower pressure to form the cylinder proper. As shown in Fig. 1 the neck portion has been drawn, and the cylinder is being drawn on the low pressure. Now should the pressure in the airometer 22 become greater than one ounce the bucket 24' will rise and begin to close the butterfly valve 26, thereby throttling the pressure from the fan 18 to the proper amount. When the pressure is again at one ounce the bucket will fall opening the butterfly valve to allow a sufficient flow of pressure from the fan. I thus secure a uniform continuous pressure which results in an even or uniform cylinder of a uniform thickness of glass. If the pressure be uneven the cylinder is alternately bulged and contracted and the thickness of the glass is consequently thinner and thicker in different portions. My invention overcomes this fault, and secures a better grade of glass.

The airometer 21 operates in the same manner, and when the valve 29 closes off communication between either branch and the supply pipe the pressure remaining in

the branch and airometer will raise the bucket and close the butter-fly valve as indicated in the left hand of Fig. 1.

In Fig. 2 I have shown a modified form 5 of my invention, the departure consisting of using but one fan to supply pressure, and in connecting both airometers with suitable piping with the fan.

The construction is simple, there is but a 10 single control rendering no delay necessary in changing pressures and I am enabled to use a cheap pressure generating apparatus, and still secure a superior quality of glass. Other advantages will present themselves to 15 those skilled in the art.

Having thus described my invention and 20 illustrated its use what I claim as new and desire to secure by Letters Patent is the following:

20 1. A glass drawing apparatus comprising in combination, a bait, drawing mechanism for the bait, a pressure supply, a supply pipe for the bait dividing into two branches, a pressure regulator in each branch, throttling valves actuated by the regulators located in the branches of the supply pipe between the regulators and the pressure supply, and a valve for controlling the admission of pressure from either branch of the 30 supply pipe.

25 2. A glass drawing mechanism comprising in combination, a bait, means for elevating the bait, a supply pipe for the bait dividing into two branches, a pressure supply for each branch, a pressure regulator in each branch, throttling valves in the branches between the pressure supplies and the regulators, said valves being operated by the pressure regulators, and a two way 35 valve for controlling the admission of pressure from either branch into the supply pipe.

30 3. A glass drawing apparatus comprising in combination, a bait, elevating mechanism 40 for the bait, a supply pipe dividing into two branches, a fan for each branch, a pressure regulator in each branch, throttling valves in the branches between the fans and the pressure regulators, said valves being actuated by the regulators, and a two way valve 45

at the juncture of the supply pipe and its branches for controlling the admission of pressure from either branch into the supply pipe.

4. A glass drawing mechanism comprising in combination, a bait, means for elevating the bait, a double pressure supply for said bait, and means between each pressure supply and the bait for automatically controlling said pressure supply to the bait. 65

5. A glass drawing mechanism comprising in combination a bait, means for elevating the bait to draw a cylinder, a plurality of pressure supplies for the bait, means automatically regulating the pressure of 60 each pressure supply, and means for connecting any one of the pressure supplies to the bait.

6. A glass drawing mechanism comprising in combination a bait, means for elevating the bait to draw a cylinder, a plurality of pressure supplies for the bait, means automatically regulating the pressure of 70 each pressure supply, and means for connecting any one of the pressure supplies to 75 the bait while the bait is being elevated.

7. A glass drawing mechanism comprising in combination a bait, means for elevating the bait to draw a cylinder, a plurality of air supplies communicating with the bait, 80 each having a different uniform pressure, means automatically regulating the pressure of each air supply, and means for opening and closing the communication between the various air supplies and the bait. 85

8. A glass drawing mechanism comprising in combination a bait, means for elevating the bait to draw a cylinder, a pressure supply system for the bait, a plurality of connections between the pressure supply and the bait, and means in each connection for automatically regulating the pressure therein. 90

In testimony whereof I have hereunto signed my name in the presence of the two subscribed witnesses.

W. L. CLAUSE.
